UNITED STATES PATENT OFFICE.

OTTO LAMWERS, OF PATERSON, NEW JERSEY, ASSIGNOR, BY DIRECT AND MESNE ASSIGNMENTS, TO L. VOELKNER AND ROSA LAMWERS, OF PATERSON, NEW JERSEY.

KNITTING-MACHINE.

SPECIFICATION forming part of Letters Patent No. 690,157, dated December 31, 1901.

Application filed April 5, 1901. Serial No. 54,509. (No model.)

To all whom it may concern:

Be it known that I, OTTO LAMWERS, a subject of the Emperor of Germany, residing in Paterson, in the county of Passaic and State of

5 New Jersey, have invented certain new and useful Improvements in Knitting-Machines; and I do hereby declare the following to be a full, clear, and exact description of the invention, such as will enable others skilled in the 10 art to which it appertains to make and use the same, reference being had to the accompanying drawings, and to letters and figures of reference marked thereon, which form a part of this specification.

15 This invention consists in an improved construction of thread or yarn feeding mechanism for knitting-machines, and especially straight-knitting machines of the Lamb type, the object being to provide an improved construction of means for rendering the machine capable of supplying both of its sets of needles instead of but one, as in many machines at present in use, with yarn each time the carriage is shifted. The invention further 20 consists in a peculiar form of needle-latch-opening mechanism adapted to be used especially in connection with my improved thread or yarn feeding mechanism.

The invention is designed for use in connection particularly with the knitting-machine described and claimed in my copending application, filed November 17, 1900, and bearing Serial No. 36,809.

The invention is fully illustrated in the accompanying drawings, wherein—

35 Figure 1 is a top plan view of a knitting-machine provided with my improved thread or yarn feeding mechanism. Fig. 2 is a view in side elevation of said thread or yarn feeding mechanism. Fig. 3 is a top plan view of a portion of one side of the carriage of the machine, showing one part of said thread or yarn feeding mechanism. Fig. 4 is a top plan view of a portion of the other side of said carriage, showing the other part of said thread or yarn feeding mechanism. Figs. 5, 6, 7, 8, and 9 illustrate details of the invention.

In order to produce circular goods in the ordinary Lamb knitting-machine, the thread

or yarn feeding mechanism is arranged to supply one set of needles when the carriage moves over and the other set of needles when the carriage returns. In my improved construction I duplicate the feeding mechanism, and while each mechanism is arranged to alternately supply the sets of needles said mechanisms work together—that is to say, in the movement of the carriage in either direction one mechanism is supplying one set of needles while the other mechanism is supplying the other. Inasmuch as the machine is adapted to work as the ordinary Lamb machine works—that is to say, with but a single yarn-feeding mechanism instead of a double yarn-feeding mechanism—I arrange one of the yarn-feeding mechanisms so that it may be thrown entirely out of action. This one I hereinafter term the "auxiliary yarn-feeding mechanism" to distinguish it from the other one, which I term the "main yarn-feeding mechanism." To distinguish the yarn-guides, which form the principal parts of these mechanisms, I term the one the "main yarn-guide" and the other the "auxiliary yarn-guide."

In the accompanying drawings, a designates the frame of the machine, the same being provided with runways *b*, on which moves a carriage *c*, which is adapted to be reciprocated from a revoluble shaft *d*, journaled in said frame at one end of the latter by a crank *e*, which is connected with a stud *f* on the carriage by a pitman *g*. The needle-beds *h* are arranged in the usual parallel inclined disposition in the frame *a*, and directly over them and carried by the carriage *c* move the cam-boxes *i i'*. At *j* in Fig. 1 are designated in dotted lines the paths which, receiving the lugs or toes *k*, with which the needles are, as usual, provided, and having incurvations sufficient for the purposes of illustrating the present invention, serve to actuate said needles, elevating the same as the carriage sweeps over them in a sort of wave-like motion. *k'* denotes the said needles. The cam-boxes are secured to arched plates *l*, constituting the transverse portions of the framing of the carriage *c*, preferably by bolts *m*. The cam-box *i'* is adapted to be shifted out of di-

rect opposition to the cam-box i for a purpose hereinafter explained, and to this end its bolts m extend through parallel slots n in the arched plates l . In order to shift the cam-box i , a lever o , pivoted at p on one of the arched plates, is provided, the same being connected with one of the bolts m , which extends through a slot q in said lever.

The main yarn-feeding mechanism is best shown in Figs. 2 and 3. r is an oscillatory lever having a slot s at one end, through which projects a screw t , which is mounted in the cam-box i , the free or upper end of this lever being bent downwardly and provided with thread-eyelets u , the lower one of which moves in alinement with the upper or acting ends of the knitting-needles when in their normal elevated or thread-receiving positions. On the upper edge of the cam-box i is secured a guide v , against the upper edge of which a pin w on the arm is held by a spring x , which presses against a boss y on the slotted end of the lever. The guide is slotted longitudinally and horizontally, and the lever projects through it, as seen in Fig. 2, its movement being thus rendered true. On a stud z , projecting from this lever, is pivoted an arm 1 , which is in two pivotally-connected parts 2 3 , the free part 3 thereof being held downwardly by a plate-spring 4 , projecting from the stud. In a lug 5 on the lever is pivotally mounted a T-shaped trip 6 , whose head 7 takes under the free end of the part 3 of the arm, the free portion of its shank after being extended through the lug 5 being turned downwardly through a transverse slot 8 in the lever. The part 3 of the arm presses downwardly on the head of the trip, engaging either the one or the other of its ends, and thus normally tilting it. It carries a downwardly-projecting pin 9 , which is adapted to be received by a slot 10 in the guide. 11 11 denote two stops projecting from the guide and adapted to limit the movement of the lever r . 12 denotes a stop in the form of a removable pin. On each of the uprights 13 13 I arrange a detent 14 , which is adapted to engage the shank of the trip, so as to oscillate the latter in its bearing in the lug 5 . Whenever the trip is oscillated, that end of its head which was last lowermost is of course now elevated, which thus elevates the part 3 of the arm, so as to withdraw its pin from the slot in the guide and permit the free end of said part 3 to slide down the head thus set at its other inclined position. At the same time the oscillation of the trip effects a shifting of the lever, which when it has moved far enough permits the arm to drop back in position, with its pin on the other side of the lever and in the slot. Thus with each vibration of the lever said lever is locked securely in position. The detents 14 are pivoted in the uprights projecting inwardly therefrom, and their free ends are held slightly above the horizontal by springs 15 . Since the

head of the trip is normally held in either of two inclined positions by the part 3 of the arm 1 , the trip will always approach each detent from the inside, with its lower end foremost; but when it engages the elevated free end of one of the detents it is shifted and as the carriage continues to move wipes over the detent. When it returns, its lower end, which is now again foremost, is not again shifted by said detent, but by virtue of the inclining and elastic mounting of the latter passes un-actuated over the same, its shifting not occurring again till the other detent is met with.

The auxiliary yarn-feeding mechanism is best shown in Figs. 2 and 4. 16 is a lever which is also oscillatory, having a longitudinal slot 17 , which receives a pin 18 , extending from the cam-box i' . On the cam-box i' is mounted a plate 19 , having a V-shaped slot 20 , in which works a stud 21 on the lever. A wire spring 22 , which is coiled about a stud 23 and which at one end bears against the plate 19 , is connected to the lever at its other end by a link 24 , said spring thus acting to throw the lever outwardly. At its free end this lever carries a head 25 , which is pivoted thereto and has thread-eyelets 26 , arranged the one above the other. Said head may also have an auxiliary thread-eye 27 between the other two. This thread-guide is adapted to be shifted by detents 28 on the uprights 13 13 , which detents pawls 29 , pivoted in a block 30 on the lever, are arranged to strike. The pawls are pressed inwardly against the sides of the lever by springs 31 . The detents 28 are pivotally mounted and are normally held elevated by springs 32 , though they are capable of yielding in either direction. The tension of the springs 32 is such that the detents offer sufficient drag to the thread-guide to shift the same, but not enough so that after the thread-guide has reached its extreme of movement it cannot be forced past the detents as the carriage proceeds in its movement. When it is desired to use the main thread-guide, the auxiliary one may be thrown out of operation by breaking off the thread which it feeds, throwing its head into the position shown in dotted lines in Fig. 2, while the whole thread-guide is moved over to the position shown in dotted lines in Fig. 4. In order that the pawls 29 may be thrown out of their usual path and so prevented from engaging the detents at this time, I provide a cam or spreader 33 , which is pivoted between the free ends of the pawls and may be turned by a thumb-screw 34 to spread them and thus elevate them. The main thread-guide leads in both directions in which the carriage moves. The object, therefore, of the V-shaped slot 20 is to withdraw the feeding end of the auxiliary thread-guide, as when each thread-guide is shifted they pass each other, and so the two threads are not interfered with. When the thread-guides are working together, the free or outer end of the main thread-guide is al-

ways foremost. The position of the other thread-guide is always just the reverse of that of the main thread-guide—that is to say, it assumes a trailing position, its pivoted end being always foremost. Projecting from the cam-box i' is an arm 35, which carries a flaring blade 36, whose points are adapted to open the latches of the knitting-needles, and thus insure said needles taking the thread. A similar blade 37 is pivoted on an arm 38, extending from the cam-box i' , the shank portion 39 of said blade being normally held against a stop 40 on the arm by a spring 41. On the arm is pivoted a lever 42, whose inner end is turned down and engages a cam 43, projecting from the shank 39 of the blade, the free arm of said lever being pressed by a spring 44. On the cam-box i' is pivoted another lever 45, carrying a pin 46 at one end, which bears against the lever 42 and is adapted to shift said lever when the lever 45 is itself shifted by the stud 21, which moves in a slot 47 of said lever. The blade 37 is pivotally mounted and automatically actuated by the mechanism just described, so that it will be thrown out of the way of the head of the auxiliary thread-guide when the latter is shifted. In view of the foregoing it will be seen that (having first shifted the cam-box i' so that its cams will when the carriage moves produce a wave-like movement in the needles of one row which is slightly in advance of the corresponding movement in the needles of the other row) by virtue of the fact that the main yarn-guide always leads when the two yarn-guides are working together as a result of its being caused to shift at each limit of movement of the carriage, said yarn-guide acts to alternately feed the two rows of needles. The other yarn-guide is of course doing the same thing. It should be remarked that the yarn is always fed to the needles just back of the crest of the wave produced therein by the cams. The main yarn-guide is adapted to be used alone, as already indicated, at which time the range of movement thereof is between the left-hand pin 11 and the pin 9, which latter being carried by the part 3 of the arm 1 works in the orifice 10, the pin 12 being removed. By reshifting the cam-box i' it is now brought to such a position that the two sets of cams are opposite each other, so as to be in proper position relatively to the main yarn-guide. It will be understood that the usual expedients for causing the cams to be alternately thrown in and out of action relatively to the needle-lugs or toes should be provided. When the main yarn-guide is thus operating alone, the detents 14 are turned over out of the way, so as not to engage the trip 6, and in order that said yarn-guide may be oscillated a drag 48, which it carries and which frictionally bears against a rod 49, supported in brackets 50 under the carriage, is provided. At this time therefore the main thread-guide simply assumes a trailing posi-

tion—that is to say, its pivoted end is always foremost in whichever direction the carriage moves.

Having thus fully described my invention, 70 what I claim as new, and desire to secure by Letters Patent, is—

1. In a knitting-machine, the combination, with the frame, of knitting-needles arranged in said frame in two corresponding series, a carriage adapted to reciprocate in said frame, means, adapted to successively engage the needles of both series substantially simultaneously first from one end and then from the other end of the two series, to actuate said needles in effecting the knitting, and separate means, pivotally mounted and movable each independently of the other on said carriage, for feeding said series of needles each time they are actuated to effect the knitting, 85 said feeding means alternating each to feed first the one and then the other of said series of needles, substantially as described.

2. In a knitting-machine, the combination, with the frame, of knitting-needles arranged in said frame in two corresponding series, a carriage adapted to reciprocate over said series of needles, means, adapted to successively engage the needles of each series first from the one and then from the other end of said 95 series of needles, to actuate said needles in effecting the knitting, and thread-feeding members pivotally mounted on the carriage and shiftable thereon in the direction of movement thereof, said members alternating each to feed 100 first the one and then the other of said series of needles, substantially as described.

3. In a knitting-machine, the combination, with the frame, of knitting-needles arranged in said frame in two series, the thread-engaging portions of the needles of the two series being movable into substantial alinement with each other, means, adapted to successively engage the needles of both series first from the one end and then from the other end thereof as the carriage reciprocates and at points in the series relatively out of opposition to each other, to actuate said needles in effecting the knitting, and thread-feeding members pivotally mounted on said carriage, one of 110 said members being shiftable to a position relatively in advance of the other and of the leading actuated needles in each movement of the carriage, substantially as described.

4. In a knitting-machine, the combination, 120 with the frame, of knitting-needles arranged in said frame in two series, the thread-engaging portions of the needles of the two series being movable into substantial alinement with each other, means, carried by the carriage, 125 and adapted to successively engage the needles of both series first from the one end and then from the other end thereof as the carriage reciprocates and at points in the series relatively out of opposition to each other, to 130 actuate said needles in effecting the knitting, thread-feeding members pivotally mounted

on said carriage, one of said members being shiftable to a position relatively in advance of the other, and detents adapted to be engaged by said last-named member to shift the same, substantially as described.

5. In a yarn-feeding mechanism for a knitting-machine, the combination, with a suitable support, of a laterally-movable yarn-feeding member arranged on said support, a locking device for said member, movable over the same and adapted to engage the support on either side of said member, and means, carried by said member, for shifting said locking device as said member moves, substantially as described.

6. In a yarn-feeding mechanism for a knitting-machine, the combination, with a suitable support, of a lever fulcrumed on said support and having a yarn-eyelet, a locking device for said lever, said locking device being pivoted on the lever and one end thereof being movable over the lever and adapted to engage said support on either side of the lever, and means, engaging said lever and the device, for shifting the same, substantially as described.

7. In a knitting-machine, the combination, with the frame, with needles and their operating mechanism and with detents, of a carriage, a yarn-guide fulcrumed on said carriage, said carriage and the detents being movable the one relatively to the other, a locking device for said yarn-guide, said locking device being pivoted on said yarn-guide and one end thereof being movable over the yarn-guide and adapted to engage said support on either side of the yarn-guide, and an oscillatory trip engaging said yarn-guide and the locking device for shifting the same, said

trip being adapted to be engaged by the de- 40 tent, substantially as described.

8. In a knitting-machine, the combination, with a suitable support, of a shiftable yarn-guide pivoted on said support, another part carried by said support and projecting into 45 alinement with and between the limits of motion of said yarn-guide, means for shifting the yarn-guide, and means for deflecting the yarn-guide away from said part when said yarn-guide is shifted, substantially as de- 50 scribed.

9. In a knitting-machine, the combination, with a suitable support and with the needles, of a movable part pivoted on said support, a needle-latch-opening blade movably arranged on said support and projecting into the path of movement of said part, and means for automatically moving said blade out of the path of said movable part upon the actuation thereof, substantially as described. 55

10. In a knitting-machine, the combination, with a suitable support and with the needles, of a shiftable yarn-guide mounted on said support, a needle-latch-opening blade movably arranged on said support and projecting 65 into the path of movement of said yarn-guide, said yarn-guide being adapted to actuate the blade, and operative connecting means between said yarn-guide and the blade, substantially as described. 70

In testimony that I claim the foregoing I have hereunto set my hand this 4th day of February, 1901.

OTTO LAMWERS.
